OXYGEN DETECTION AND MEASUREMENT

Edward L. Kells, Milwaukee, Wis., and Delmar H. Larsen, West Hollywood, Calif.

Application July 13, 1949, Serial No. 104,576

5 Claims. (Cl. 175—183)

1

This invention relates to the art of detecting oxygen when present in a gas, and more particularly to a new method of determining when oxygen is present and of determining its concentration quantitatively, and of controlling oxygen concentrations. This application is a continuation-in-part of our successively copending applications Serial No. 481,800, filed April 5, 1943, now abandoned, and Serial No. 618,492, filed September 25, 1945, now Patent No. 2,476,304.

In many fields it is of great importance to know how much oxygen is present in a given gas. For example, the oxygen content of the flue gases from combustion processes gives an indication of the efficiency of the combustion; many chemical processes involving gaseous reactions depend for proper control upon the oxygen content of the feed or output gases; where air is used to support life and liability of oxygen depletion is present the necessity of knowing the oxygen concentration is obvious.

In all such applications it is highly advantageous, and generally absolutely necessary, to have the analytical results immediately available. While oxygen concentrations can be determined by standard chemical methods of gas analysis, the delay introduced thereby generally renders the analysis useless, as it is then too late to make any indicated changes in operating conditions. Accordingly, many devices have been developed which carry out, by one means or another, a rapid analysis of a gas for oxygen, and usually provide the result in such form that it can be continuously recorded. Unfortunately most such devices are mechanically complex, depending as they do upon characteristics of oxygen not readily adaptable to simple and foolproof measurement, and thus not only are expensive but require expert attention.

At the same time it is not only necessary to know what the oxygen concentration is in the environments mentioned as examples, but it is also highly advantageous to provide means of controlling the concentrations at desired levels. When this is done the disadvantage of having time lag in the system is self evident.

It is an object of the present invention to enable oxygen concentration determinations to be made in a new and novel manner which is particularly adapted to simple mechanical embodiments.

Another object of the invention is to provide new and novel means for controlling oxygen concentrations and processes dependent upon the latter.

Another object of the invention is to provide a means of determining oxygen concentrations instantaneously.

Other objects of the invention will appear as the description thereof proceeds.

Broadly stated, according to the present invention the oxygen content of a gas is found (and if desired, controlled) by determining, directly or by a function thereof, the magnetic susceptibility of the gas in question and relating the value so found to the oxygen content. It is possible to do this because, of all the gases commonly occurring in the fields of application of this invention, oxygen is the only one possessing paramagnetism; all other commonly occurring gases, such as nitrogen, carbon dioxide, carbon monoxide, sulfur dioxide, sulfur trioxide, hydrogen and gaseous hydrocarbons are diamagnetic. Moreover, the absolute value of the volume magnetic susceptibility of oxygen, (that is, susceptibility per unit volume), is more than 100 times that of most other common gases, and in fact is about 230 times that of the non-oxygen portion of ordinary flue gases. The following values are illustrative:

Gas	Volumer Susceptibility (1 Atm., 20° C., C. G. S. units $\times 10^9$)
Pure Oxygen	+142
Pure nitrogen	-0.58
Pure carbon dioxide	-0.78
Pure hydrogen	-0.16
Pure methane	-0.7
Pure carbon monoxide	-0.5
Flue gas, 15% oxygen	+20.8
Flue gas, 10% oxygen	+13.6
Flue gas, 5% oxygen	+6.5
Air	+29.0

The volumer susceptibility of both para and diamagnetic gases will change in direct proportion to the pressure; that of oxygen changes substantially inversely with the absolute temperature, and that of the diamagnetic gases is substantially invariable with temperature, volumes maintained constant. As the susceptibility of mixed gases is substantially additive with respect to the partial volumes present, it is an easy matter to calculate the susceptibility of a given gas, for example flue gas containing 10% oxygen, at any desired pressure and temperature from the relations just stated.

Thus, according to the invention, the susceptibility of the gas sample is determined, and the value obtained is suitably corrected for temperature and pressure as indicated above, and the

value so obtained is compared with the figures given in table above. The comparison is facilitated by plotting the values on a graph, as the relationship between oxygen content and susceptibility is linear for the ordinary gases comprised in the fields of application of this invention.

Not only will we proceed to show how the process of the invention may be carried out, but also it will be shown how the operation described above can be done as completely mechanically as desired, so that corrections for temperature and also for pressure are automatically made and final readings obtained directly in terms of oxygen content, either as a partial pressure or a volume percentage. Also we will show how control of oxygen concentration can be automatically achieved.

Reference is now made to the drawings accompanying this specification; therein:

Figure 1 shows a form of apparatus which is suitable;

Figure 2 shows a variation of detail in the apparatus of Figure 1.

In Figure 1 an electromagnet 10 is excited by an alternating current coil 11. The pole pieces in this instance are shaped to give maximum field strength in a relatively small space between them; gradient of field strength is of no particular importance. There are inserted into the field between the pole pieces two rods, 12 and 13, which almost touch in the strongest part of the field. These rods maintain a substantially constant cross-sectional area until the limits of the strong portion of the magnetic field are reached, whereupon they taper out and terminate at the "needles" of two ordinary pickups, 15 and 16, such as are used for phonograph record reproduction. The rods are positioned by supports 17 and 18, which may be rubber collars or the like. The two pickups are connected to an amplifier, at least the first stage of which is a push-pull stage, and the basic parts of which are schematically indicated in Figure 1. The pickups are connected with respect to polarity so that when both rods are mutually repelled or mutually attracted, the two grids of the first stage are given opposite polarities so that an impulse results in the secondary of the transformer 19. Conversely, with such an arrangement, movement of the two rods in the same direction, with unchanged mutual separation, will result in changes in primary currents in the transformer 19, which cancel each other and give no impulse. Potentiometer 25 can be adjusted to balance out inequalities between the two outputs. An alternating current output meter 20 is placed across the output of the amplifier, which may, of course, contain more stages of amplification than shown if necessary. The output meter 20 is calibrated in units of oxygen partial pressure. An enclosure 21 is placed around the electromagnet and is fitted with tubulations 22 and 23 whereby the enclosure can readily be filled with the gas to be tested.

The rods 12 and 13 are constructed of a hard, durable substance having a susceptibility which for best results is approximately within the range of that of the gases to be tested. A suitable material is an aluminum-zinc alloy containing about 45% zinc, or a platinum tube containing a close fitting antimony rod, of suitable mutual proportions. Glass or plastic rod, containing a core of a sufficient proportion of paramagnetic material such as platinum, aluminum, tourma-

line, ebonite and the like may be used. Of these, those which do not conduct electricity throughout the mass are preferable because damping by eddy currents is thereby avoided. Here generally it is preferable to have the volumar susceptibility of the rod or rods within the approximate limits of -10×10^{-9} to $+150 \times 10^{-9}$ volumar C. G. S. units.

The mode of operation of the apparatus of Figure 1 is as follows: When a gas which is more paramagnetic than the rods 12 and 13, surrounds the latter, the rods will tend to move out of the magnetic field, which of course occurs when the magnet is excited by current during a portion of the alternating-current cycle. When the magnetic field is zero, as occurs approximately at the time when the alternating current is changing direction, the tendency to move out of the field will cease, and the rods will spring back into place. When the current is reversed during the second half of the cycle, the magnetic field will again rise to a maximum and the rods will be repelled. Thus, if the current energizing the magnet has a frequency of 60 cycles per second, the rods will vibrate 120 cycles per second. If the gas is less paramagnetic than the rods, the latter will tend to move into the field during the period when the magnetic field is present.

Now the force attracting or repelling the rods is, other variables being unchanged, directly proportional to the algebraic difference of the volumar susceptibilities of the gas and the rod, and therefore a direct function of the oxygen content of the gas. Since the E. M. F. developed by the pickups is a function of that force, and can be suitably amplified and transformed into a meter reading, the ability of this device to read oxygen directly is at once apparent. The meter may be of the indicating type, as shown in Figure 1 or it may be a recording meter. For the general case, an alternating current milliammeter is used, although a rectifying device such as a tube or copper oxide disc-pile can be placed in the output circuit so that a direct current meter may be used. It is advantageous to have the meter scale calibrated directly in units of oxygen concentration; also, the output of the amplifier can be connected to a control mechanism, as described more fully hereinbelow.

A method of automatic temperature compensation incorporable into the apparatus of Figure 1 will now be described. Since the mass susceptibility of oxygen varies inversely as the first power of the absolute temperature, and since the isobaric volume of oxygen also varies inversely with the first power of the absolute temperature, the isobaric volume susceptibility evidently varies inversely as the square of the absolute temperature. Now for the region of ordinary room temperatures, this amounts to a change of approximately 0.67% per degree centigrade. Accordingly, if a resistance 26 having a temperature coefficient of that amount is placed in the gas to be measured, and also is simultaneously placed in the electrical circuit by means of leads 27 and 28 so that it will change the output of the amplifier by that amount, then the amplifier gain will be automatically compensated for changes in temperature.

While nearly any frequency of alternating current may be used to energize the magnet, ordinary 50 or 60 cycle current is particularly convenient in actual application. Whatever frequency is used, care should be taken to adjust the resonant frequency of the mechanical vibrating

system to such a value as will assure smooth response to the energizing force, in accordance with well-known laws of mechanically resonant systems.

It is desirable to make the system independent of externally imposed shocks, vibrations, accelerations and rotations so that installations where severe operating conditions prevail, such as in warships, are feasible. This can be done in several ways, as now discussed in detail. First the arrangement of the armature rods 12 and 13, in Figure 1, with the pickup output connected in push-pull as described hereinabove, largely avoids such troubles. Moreover, both armature rods can be L shaped and can be pivoted and so designed as to be in both dynamic and static balance; in fact such a design of the armature is particularly advantageous where only one armature rod is used. The general design of such a pivoted armature is shown in Figure 2, where 30 and 31 are the pole pieces of the magnet, 32 is the pivoted armature with at least the portion 33 which projects into the strong part of the field being of material of suitable susceptibility, and 34 is the pivot, rotation about which point allows the end of the armature 33 to move in and out of the magnetic field. 35 is a single pickup, the leads of which, 36, are connected to an amplifier, not shown.

Freedom of instrument reading from vibration can also be achieved for instruments working on the general type of Figure 1 by causing the amplifier to be selective for the driving frequency of the electromagnet. For example, a sharply peaked band pass filter may be incorporated into the amplifier circuit, which will pass only the frequency generated by the magnetic field, and will not pass the frequency vibrating armature which as explained hereinabove will in general be different from the former.

Again, some of the alternating current from the source which energizes the electromagnet can be passed through a phase shifting circuit, then rectified, and, without filtering, used to supply grid or plate voltage for some convenient tube in the amplifying circuit, so that that tube amplifies only those impulses which are of a frequency and phase derivable from the action of the pulsating magnetic field on the armature assembly. Of course, the exact manner of application of these various amplifying current refinements will be evident to an electronic engineer, and need not be detailed herein.

In most cases where oxygen concentrations are of interest it is desirable to control the processes or conditions giving rise to the particular concentrations encountered. Usually an oxygen concentration within certain fixed limits indicates optimum operation; when those limits are exceeded, it is desirable to change operating conditions to bring the concentration back to normal. Thus, in a gas-fired boiler flue, less than about 1% oxygen indicates the necessity of increasing the air-gas input ratio if efficient combustion is to be maintained. If the flue gas rises above about 3% oxygen, then the air-gas ratio should be

reduced. Again, in supercharged airplane cabins, submarine interiors, or the like, the oxygen concentration must be controlled within certain limits.

5 The devices embodying the present invention can be readily adapted to such an automatic control, by causing the oxygen content indicator to operate relays or the like which are in turn connected to the primary variable mechanisms, such as oil, gas, air and oxygen inlet valves, dampers, coal stokers, and the like.

10 It will be understood that while several devices have been described in detail hereinabove, multitudinous modifications can be made therein within 15 in the broad scope of the invention. Also, while as many separate embodiments as conveniently desirable within the proper limits of conciseness have been disclosed, it will be understood that the invention broadly embraces many other modifications, and is not necessarily limited to the particular devices shown herein.

We claim:

1. An apparatus for the determination of the oxygen content of a mixed gas containing oxygen, 25 comprising, an alternating current magnet, providing an alternating magnetic field, an object capable of being surrounded by said gas, and positioned in said alternating magnetic field, so that one portion is in a relatively strong part of the field and another portion is in a relatively weak part, restraining means to substantially inhibit translational motion of the object while permitting it to vibrate, and a vibration receptor operatively connected with said object, and oxygen 30 indicating means operatively connected to said vibration receptor.

2. An apparatus of the type of claim 1, in which the object has a volume magnetic susceptibility approximately within the range of -10×10^{-9} to -150×10^{-9} C. G. S. units.

3. An apparatus of the type of claim 1, in which the object is statically and dynamically balanced.

4. Apparatus for measuring the oxygen content of a gas, comprising means forming a chamber for 45 holding the gas, a magnet having a gap disposed within said chamber, means for energizing said magnet with alternating current, armatures movably mounted within said gap, a pickup connected with said armature, a voltage amplifier connected 50 to said pickup, and an indicating member connected with said voltage amplifier.

5. Apparatus of the type of claim 4, in which the armature material has volume magnetic susceptibility approximately within the range of -10×10^{-9} to -150×10^{-9} C. G. S. units.
